UNITED STATES PATENT OFFICE.

MAX KOHLSDORF, OF BROOKLYN, NEW YORK.

KNITTING-MACHINE.

1,075,262.

Specification of Letters Patent. Patented Oct. 7, 1913.

Application filed December 16, 1912. Serial No. 736,806.

To all whom it may concern:

Be it known that I, MAX KOHLSDORF, residing at Brooklyn, in the county of Kings and State of New York, have invented certain new and useful Improvements in Knitting-Machines, of which the following is a specification.

The present invention relates to knitting machines and particularly to a device for forming barrier stitches to prevent the knitted fabric from ripping open throughout its length, in case one or more stitches break. Such barrier stitches are particularly required in stockings, as it frequently happens that in the upper portion of the stocking one or more stitches break, incident to the use of gripping devices on stocking supporters. The hitherto used method of forming such barrier stitches is complicated and entails considerable loss of time.

My invention substantially consists in the combination with an ordinary knitting machine, of a device comprising a thread guide, which is arranged in opposition to the knitting needles and is given such a movement as to feed an auxiliary thread in form of a coil around each knitting needle, the coil forming a barrier between two portions of the knitted fabric, as for instance, in stockings, between the upper and lower portion and preventing the ripping from extending from one portion of the fabric to the other. It is immaterial where the barrier stitch is formed, but in practice, and particularly in the manufacture of stockings, it is preferred to form the same along the lower edge of the doubled-up upper portion of the stocking.

My invention will be more clearly understood by reference to the accompanying drawing in which similar reference letters denote corresponding parts and in which—

Figure 1 is a vertical section through the device, illustrating also a part of the knitting machine to which the device is applied; Fig. 2 is a cross section on line 2—2 of Fig. 1; Fig. 3 is a cross section on line 3—3 of Fig. 1; Fig. 4 is a detail of construction; and Figs. 5 and 6 illustrate the method of operation of the device.

The device for forming the barrier stitches comprises a guide *d* for an auxiliary thread *e* (Figs. 1 and 4) arranged in opposition to the knitting needles and capable of swinging through the space between two adjoining knitting needles and of moving crosswise

to the set of the needles. Owing to this double motion this guide feeds the auxiliary thread *e* in form of a coil *S* around each knitting needle (Fig. 5) which thread is thereby caused to embrace each longitudinal thread *S*.

In the present embodiment of my invention *a* denotes a part of the frame of the knitting machine, *b* denotes the bars for the knitting needles and *c* the knitting needles. These parts are all of ordinary construction and the needles operate in well known manner, so that a further description of the knitting machine is unnecessary. The guide *d* is in form of warped bar, the lower end *d'* of which is provided with eyes *d''* through which the thread *e* coming from a spool (not shown) is passed. The lower end *d'* is of a thickness corresponding to the space *c'* between two adjoining knitting needles *c*, so that it can freely swing through said space. Its lower edge *d''* is carved or rounded so that while it swings through the space between two adjoining knitting needles, it will not cut or even touch the threads of the fabric. The guide is fixed to the extension *f* of a shaft *g*, which is arranged parallel to and at some distance away from the edges of the knitting needles. The shaft is movably borne in a casing *m* so as to be capable of moving longitudinally and also rocking around its longitudinal axis. The longitudinal feeding movement is effected by means of a rack *h* provided on the shaft, with the teeth *h'* of which co-operate two pawls *i* and *j*. The pawls *i* and *j* are pivoted to a spring actuated rocking arm *k* fulcrumed at *k'* and carrying a roller *k''*. A disk *l* fixed on a manually operated spindle *l'* is formed on its circumference with cam shaped projections *l''* which act against the roller *k''* imparting a swinging motion to the lever *k*. The cam projections are so admeasured that by the swinging movement of the lever *k* the pawl *i* will feed the shaft intermittently forward a distance equal to two knitting needles. A weight *p* suitably suspended at *p'* from the shaft *g* tends to retract the shaft after each movement, which retraction is limited to a distance equal to the thickness of an individual knitting needle by the second pawl *j*.

The rocking movement of the guide *d* is effected through the medium of a vertically reciprocating bar *n* which has longitudinal recesses *n'* whereby it is movably mounted

on stationary projections o . This bar carries a roller n^2 (Fig. 2) that is acted upon by the cams l' of the disk l . At its free end this bar is formed with a nose n^3 which engages a longitudinal groove h' in the shaft h . As the bar through the medium of the roller n^2 and the cam disk l is caused to reciprocate the shaft h and consequently the guide d are given short swing-
10 ing movements. The two rollers k^2 and n^2 are so arranged relative to one another, that one will enter onto the ascending part of the cam projections l' earlier than the other, whereby the shaft will first receive
15 one and then the other movement. The operation of the device can be effected by a handle (not shown) to be applied to the shaft l^2 of the disk l . As this disk is revolved the shaft g will be first rocked
20 to swing the guide d through the space c' between two adjoining knitting needles c , then it will be fed a distance of two knitting needles forward, moved back one needle, then again swung in reverse direction
25 through the space c' and again fed a distance of the two knitting needles, and so on. And during these movements of the auxiliary needle the auxiliary thread e of the guide d will describe the path indicated by the coils S^3 in Fig. 5. When the work is finished the thread e forms the seam F (Fig. 6) which acts as barrier between the lower and upper end of the
30 fabric.

What I claim and desire to secure by Let- 35
ters Patent is:

1. In a knitting machine, the combination with the knitting needles, of a device for forming barrier stitches, comprising a guide directed toward the knitting needles 40 and adapted to feed an auxiliary thread in form of a coil around each individual knitting needle.

2. In a knitting machine, the combination with the knitting needles, of a device for 45 forming barrier stitches, comprising a guide having an auxiliary thread directed toward the knitting needles and means for imparting to said guide a swinging motion and a motion transversely to the knitting 50 needles, whereby the said guide will be caused to feed its thread around each individual knitting needle.

3. In a knitting machine, the combination with the knitting needles, of a device for 55 forming barrier stitches comprising a guide having an auxiliary thread directed toward the knitting needles, a member carrying said guide, means for imparting a rocking movement to said member and for feeding 60 the latter transversely to said knitting needles.

In testimony whereof I affix my signature in presence of two witnesses.

MAX KOHLSDORF.
